Attest:

UNITED STATES PATENT OFFICE

FRED C. AREY, OF OAK PARK, ILLINOIS, ASSIGNOR TO JOHN W. GLEASON, OF PITTSBURGH, PENNSYLVANIA; FRANK W. BORA, OF NEW YORK, N. Y.; WILLIAM F. FREUDENREICH, OF KENILWORTH, ILLINOIS; AND FREDERICK H. CHETLAIN, OF CHICAGO, ILLINOIS; AND HIMSELF, AS TRUSTEES

RIBBED EXPANDED-METAL LATH

Application filed July 28, 1927. Serial No. 208,915.

The present invention relates to expanded metal lath of the ribbed type, and has for its object to improve the same.

Specifically considered, my invention has for its object to produce an expanded metal that will have the strength and rigidity of expanded metal provided with heavy solid ribs while permitting the plaster to be effectively keyed and exposed to the air on both sides; thereby securing desired strength and rigidity in the lath with effective keying of the plaster and without requiring the plaster to dry unevenly and crack.

A further object of the present invention is to produce a ribbed expanded metal in which all of the longitudinals have their flat faces parallel and lying at an angle to the plane of the sheet, whereby the plaster may be evenly spread across the same in a single motion or sweep.

A further object of the present invention is to produce an expanded ribbed metal lath that will require a minimum amount of plaster for keying purposes.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a plan view of a fragment of a flat sheet showing the arrangement of slitting to produce my improved lath; Fig. 2 is a plan view of a fragment of the expanded sheet; Fig. 3 is a section taken approximately on line 3—3 of Fig. 2; Fig. 4 is a section taken approximately on line 4—4 of Fig. 2 on a larger scale; and Figs. 5 and 6 are views similar to Figs. 3 and 4, respectively, showing a modification.

In carrying out my invention the metal sheet is divided into alternating solid and slotted sections. Furthermore, the slits in alternate sections are parallel with the longitudinal axis or long edge of the sheet, while the slits in the remaining sections are arranged at an acute angle to such axis. In Fig. 1 the solid sections are indicated at A,

the sections having longitudinal slits are indicated at B; and the sections in which the slits are more or less diagonal are indicated at C.

In expanding the sheet the sections C become a diamond mesh certain of whose strands are longitudinal; the solid or ribbed portions are deformed so as to lie at an angle to the plane of the sheet and parallel with the broad faces of the longitudinal strands; and the sections B are deformed so as to produce strands bowed out of the plane of the sheet, the ends of the strands remaining in such plane. The strands of the sections B may all be bowed so as to lie on one side of the sheet as shown in Figs. 2, 3 and 4, or they may be bowed alternately in opposite directions from the sheet, as shown in Figs. 5 and 6.

Referring to Figs. 2, 3 and 4, it will be seen that the slit sections A have all been bent to form continuous longitudinal ribs 1 lying parallel with each other but at an angle of about sixty degrees to the plane of the sheet; or it may be said that the members 1 constitute flanges on the slit sections, lying at an acute angle thereto. The sections C have been transformed into a diamond mesh composed of longitudinal strands 2 lying with their flat faces parallel with the flat faces of the ribs 1, and transverse strands 3. It will be seen that when plaster is swept transversely across the sheet the resistance offered by all of the longitudinals will be uniform. The sections B are expanded by bowing the strands out of the plane of the sheet to form loops 4; the strands being stretched in order to provide the requisite length of metal to produce the bow effect.

It will thus be seen that the sheet, when expanded, comprises reticulated sections alternating with comparatively narrow solid sections; the reticulated sections differing in character, some of them being in the form of diamond mesh and the others being of a character as not to provide openings as large as in the diamond mesh, and therefore conserving plaster while permitting a sufficient amount of plaster to pass through the same to form effective keys.

In Figs. 2 to 4 all of the bowed strands lie

on one side of the sheet. If desired, some of the strands may be pressed down and the others up, as shown in Figs. 5 and 6; the strands 4 corresponding in position to the strands 4 in Figs. 2 to 4, and the strands 5 lying on the opposite side of the sheet.

While I have illustrated and described with particularity only a single preferred form of my invention, I do not desire to be limited to the exact structural details thus illustrated and described; but intend to cover all forms and arrangements which come within the definitions of my invention constituting the appended claims.

15 I claim:

1. A sheet of ribbed expanded metal comprising reticulated sections alternating with solid sections, alternate reticulated sections being expanded in the plane of the sheet, and 20 the remaining reticulated sections having strands bowed out of the plane of the sheet.

2. A sheet of ribbed expanded metal comprising reticulated sections alternating with solid sections, alternate reticulated sections 25 having strands formed by slits lying at an acute angle to the long axis of the sheet, and the remaining slotted sections having strands formed by slits arranged parallel with said axis.

30 3. A sheet of ribbed expanded metal comprising open sections alternating with solid sections, alternate open sections being formed of strands crossing each other, and the remaining open sections retaining the width of 35 the corresponding portions in the original unexpanded sheet.

40 4. A sheet of ribbed expanded metal containing solid sections bent along a longitudinal line to form parallel flanges lying at an 45 angle to the plane of the sheet, reticulated sections adjoining said flanges and having longitudinal strands whose broad faces are all parallel with said flanges.

50 5. In a sheet of ribbed expanded metal, a 45 solid longitudinal section and an adjoining reticulated section, said solid section having a portion adjoining the reticulated section lying at an angle to and projecting beyond the plane of the original sheet, and said reticulated section being in the form of diamond mesh some of whose strands form continuous longitudinal elements in the sheet and having broad faces lying parallel to the afore- 55 said portion of the solid section adjoining the reticulated section.

60 6. A sheet of ribbed expanded metal having reticulated sections alternating with panels whose marginal longitudinal portions 65 are parallel and lie at an angle to and on opposite sides of the original plane of the unexpanded sheet, and said reticulated sections consisting of transverse strands connected at the ends to said marginal portions and longitudinal strands all of whose broad faces are

parallel to said marginal portions of the solid sections.

7. An expanded metal sheet comprising longitudinal panels having their marginal portions bent laterally out of the plane of the sheet to form parallel flanges, the central portions of the panels having strands bowed out of the plane of the sheet, and the laterally expanded sections having longitudinal strands parallel with said flanges.

In testimony whereof, I sign this specification.

FRED C. AREY.
